UNITED STATES PATENT OFFICE.

CLINTON R. BARRY, OF FORT SMITH, ARKANSAS, ASSIGNOR OF ONE-HALF TO ROBERT L. SMITH, OF TULSA, OKLAHOMA.

SWIVEL ATTACHMENT.

Application filed January 6, 1926. Serial No. 79,692.

This invention relates to new and useful improvements in a swivel attachment.

One object of the invention is to provide a swivel attachment designed to be used in connection with the well known type of rotary swivel, used in well drilling by the rotary process, and by the use of which a single pair of elevators may be constantly carried by the traveling block for connection to the swivel during the drilling process, as well as for use in handling the drill pipe while the same is being made up in lowering it into the bore, or is being broken up in the process of withdrawal from the bore.

In rotary drilling it is now the practice to equip the traveling block with a C-hook which serves, at frequent intervals, to connect the traveling block to the bail of the swivel being used while drilling; or the bail of the elevator, used for handling the drill pipe, at such times as it becomes necessary to suspend drilling operations to pull the drill pipe from, and return, it into the bore. In breaking up and pulling this pipe, as commonly done the swivel and drill pipe connected thereto are elevated until the upper joint, or "grief pipe" can be disconnected. This grief pipe with swivel attached is then swung to one side and lowered into the "rat hole" and the C-hook is removed from the swivel bail and connected to the drilling hook, and this hook is then connected to the elevator bail and the elevators are then applied to the drill pipe and the same is elevated and broken up into sections and removed from the bore. In order to lower the pipe back into the bore to resume drilling the above described operations must be again performed in the reverse order.

By the use of the swivel attachment herein described these operations may be much simplified by the use of an elevator which is constantly carried by the traveling block and a type of swivel attachment connected to the swivel, and designed to receive the elevators, whereby the elevators may be connected to the swivel while drilling proceeds and applied to the drill pipe in withdrawing the same from, or lowering it into the bore.

With the above and other objects in view this invention has particular relation to certain novel features of construction, operation and arrangement of parts, an example of which is given in this specification and

illustrated in the accompanying drawings, wherein:

Figure 1 shows a front elevation of a rotary swivel, with the attachment applied thereto and shown partly in section, and

Figure 2 shows a side elevation thereof.

Referring now more particularly to the drawings, wherein like numerals of reference designate similar parts in each of the figures the numeral 1 designates the upper joint of the drill pipe. This joint is commonly known as the grief pipe, as it is operatively connected with the rotary drilling machine which drives the drill pipe beneath. The numeral 2 designates the swivel as a whole. This swivel has a swiveling connection with the grief pipe and is provided with a goose neck 3, providing for the connection of a hose to the swivel, through which water is pumped down through the drill pipe into the bore. The swivel has the oppositely disposed trunnions 4, 4, to receive the bearings 5, 5, into which the lower ends of the respective arms 6, 6, are formed. The upper ends of these arms are overturned and of arcuate formation thus presenting the confronting arcuate clamps 7, 7, whose ends have outwardly turned ears 8, 8, which abut and are bolted together to form an annular clamp collar which is secured around the tubular body 10, of the attachment. Above and below this clamp collar the body has the external annular retaining flanges 11 and 12 respectively. The body 10 is held in upright position, relative to the swivel by means of a surrounding element 13, such as a cable which is secured to the arms 6, and surrounds the upper end of the swivel proper.

The body 10 is extended above the retaining flange 11 thus providing a blank neck 14 to receive the ordinary type of elevators, as 15. The upper end of the neck 14 has an external annular flange 16 for retaining the elevators in place and also has an eye 17, for convenience in handling the attachment 100 and this eye has oppositely disposed ears 18, 18, adapted to engage in the elevator bails, or links, 19, 19, to prevent the swivel from turning and twisting or disrupting the rotary hose, above adverted to, in drilling.

While drilling is in progress the swivel will be suspended, by the elevators, from the traveling block as shown. When it is desired to withdraw the drill pipe the same may be elevated and broken up and then

made up and again lowered into the bore, by the use of said elevators in the usual way without disconnecting the elevators from the traveling block. It is obvious that with a swivel adapted for a small size of pipe an elevator adapted for larger pipe may be used by inserting a suitable bushing, as 20, within the elevator.

What I claim is:

10. 1. An attachment for swivels including side arms adapted to be pivotally connected to and to upstand from a swivel, a clamp collar carried by the upper ends of said arms, a tubular body fitted through said collar, retaining means retaining said body in said collar, said body being extended, forming an elevator receiving neck.
15. 2. An attachment for swivels including side arms adapted to be pivotally connected to and to upstand from a swivel, a clamp collar carried by the upper ends of said arms, a tubular body fitted through said collar, retaining means retaining said body in said collar, said body being extended, forming an elevator receiving neck and an external elevator retainer carried by the upper end of said neck.
20. 3. An attachment for swivels including side arms adapted to be pivotally connected to and to upstand from a swivel, a clamp collar carried by the upper end of said arms, a tubular body fitted through said collar, retaining means retaining said body in said collar, said body being extended, forming an elevator receiving neck and lateral ears carried by the upper end of said body adapted to engage the elevator bails.
25. 4. An attachment adapted for connection to a rotary swivel and having a neck adapted to receive a pipe elevator, elevator retaining

means on said neck above the swivel, and means for retaining said attachment in upright position relative to the swivel.

5. The combination of a swivel attachment having a plurality of flanges therearound adapted to be connected to a swivel and having a neck, of a pipe elevator adapted to be applied to said neck between two of said flanges and clamp arms also connected to said swivel and to said attachment. 45

6. The combination of a swivel attachment having a plurality of flanges therearound and adapted to be connected to a swivel and having a neck, of a pipe elevator adapted to be applied to said neck between two of said flanges and clamp arms also, connected to said swivel and to said attachment and a bushing interposed between said elevator and neck. 55

7. An attachment for swivels including means adapted to be pivotally connected to and to upstand from a swivel, a clamp collar carried by the upper end of said means, a body fitted through said collar, retaining means retaining said body in said collar, 60 said body being extended, forming an elevator receiving neck.

8. An attachment for swivels including side arms adapted to be pivotally connected to and to upstand from a swivel, a clamp collar carried by the upper ends of said arms, a body fitted through said collar, retaining means retaining said body in said collar, said body being extended, forming an elevator receiving neck and an external elevator retainer carried by the upper end of 70 said neck. 75

In testimony whereof I have signed my name to this specification.

CLINTON R. BARRY.
